Attn: S.

UNITED STATES PATENT OFFICE

GEORGE F. HARTER, OF SPRINGFIELD, MASSACHUSETTS, ASSIGNOR TO THE STANDARD ELECTRIC TIME COMPANY, OF SPRINGFIELD, MASSACHUSETTS, A CORPORATION OF CONNECTICUT

ELECTRIC TIME CLOCK CORRECTION

Original application filed October 15, 1927, Serial No. 226,317. Divided and this application filed July 27, 1928, Serial No. 295,782. Renewed October 6, 1930.

My invention relates to electric clocks and electric clock systems of the type wherein a master clock which is very accurate controls, by means of electric circuits, the operation of several less expensive secondary clocks, and more particularly to those secondary clocks which operate wholly by means of electric impulses received from the master clock.

Periodically, usually each minute, such 10 clocks are advanced by an electric impulse from the master clock. In the course of 24 hours there are 1440 such impulses and if for any reason such impulses fail even once, the secondary clock or clocks will show incor- 15 rect time. If all secondary clocks become slow the same amount they may be advanced by hand by a set key usually provided at the master clock for that purpose. But sometimes, because of a weak battery for example, 20 some secondary clocks fail to receive sufficient current to operate them more often than others. It then becomes necessary to make the rounds of all the secondary clocks and set them individually or at least make sure 25 they need no setting.

One purpose of my invention is to provide for the automatic setting of the secondary clocks at less frequent intervals than the operating impulses are sent; and to automatically bring all secondary clocks to the same time regardless of whether they are all in error the same amount. My invention also 20 makes it possible to set groups of secondary clocks from the master clock instead of individually because my invention not merely advances the secondary clocks, but actually sets them. I prefer to set these secondary clocks once each hour, although it is obvious that other intervals may be selected and I do not 25 wish to confine myself to an hourly setting.

Heretofore a source of electricity, either primary or storage batteries, has been selected which would be as dependable as possible. Because of the danger of interruption of central station power due to blown fuses or other causes, such power has very rarely been used. But because of the frequency and certainty with which the secondary clocks are set by means of my invention, it is no longer 30 necessary to provide at great expense against

all minor interruptions of the source of current supply. I do not mean that I have dispensed with batteries in all cases but the objection to any source of power because it is subject to minor interruption is no longer 35 as serious as formerly.

For the purpose of illustrating the genius of the invention one concrete embodiment is shown in the accompanying diagram, this embodiment being adapted for use in any 40 suitable system such, for example, as disclosed in copending application Serial No. 226,317, filed October 15, 1927, of which this is a division.

At 34 is shown generally a secondary clock 65 mechanism embodying the present invention. Those parts which are old but necessary to an understanding of my invention will be described first. The shaft 35 is rotated once each hour. Carried by the shaft 35 is a 70 ratchet wheel 36 which is impelled forward once each minute by the pawl 37 carried by the lever 38. Lever 38 is pivoted at 39 and carries an armature 40 which is attracted by magnet 41. A second ratchet wheel 42 is also 75 carried by shaft 35 and in cooperation with pin 43 prevents shaft 35 from jarring forward during the time between impulses. Pawl 44 prevents backward rotation of shaft 35 and spring 54 retracts lever 38 after magnet 41 80 has ceased to attract armature 40.

In addition to the usual mechanism described in the foregoing paragraph I employ a corrective magnet 45 which operates on the armature 46 which is carried by stop 85 lever 55. Lever 55 is pivoted at 47 and carries a stop 48, a second stop 49 slightly advanced from the first stop, and a pin 50. Non-rotatably attached to shaft 35 is a cam 51 carrying a pin 52 and having a cam face 90 53 adapted to be actuated by pin 50.

As shown in the figure, the stop 48 normally stands in the path of pin 52 on cam 51 and if the clock hands actuated by 35 get ahead of time stop 48 stops further advance 95 of the clock beyond the 59th minute position until corrective magnet 45 is energized on the hour to move the stop 48 out of the path of pin 52. If the clock has lost time during the hour, pin 50 engages cam 53 to advance 100

the hands to the hour position when magnet 45 is momentarily energized at the end of the hour, stop 49 then moving into the path of pin 52 to limit the advance precisely to the hour position. The engagement of pin 50 with cam face 53 will advance the cam 51 until pin 52 engages stop 49, whether the clock is on time or behind time or ahead of time, and owing to the fact that stop 49 is slightly ahead of stop 48 the return of stop 48 to normal position can not block pin 52. The pin 52 may be provided with a beveled top as shown in the figure so that it will come under stop 48 if it does not entirely clear the stop as lever 55 returns to normal position.

Thus impulses transmitted to magnet 41 through conductors 58 and 59 (by suitable mechanism such as disclosed in said application for example) at suitable intervals, such as once per minute, cause the clock hands to advance intermittently; and at the end of each hour (or at other predetermined intervals) an impulse is transmitted through conductors 59 and 61 (by suitable mechanism such as disclosed in said application for example) to corrective magnet 45 at the same time as magnet 41 is energized, thereby causing the secondary clock 34, as well as other similar clocks connected in parallel therewith through conductors 58', 59' and 61', to start the new hour on time irrespective of any inaccuracy developed during the preceding hour as above described.

It will thus be seen that I have provided a simple and accurate means for rectifying errors of the secondary clock at definite intervals of time and to bring all secondary clocks into exact agreement whether fast, slow or correct and whether they all have the same error or different errors.

From the foregoing it will be evident that the present invention comprises a secondary clock of the type normally operable by recurrent impulses from a master clock characterized in that the resetting means is responsive to current of either polarity, thereby eliminating the unreliability of polarized magnets. Moreover such non-polarized means is of course ordinarily responsive to alternating current. Another important characteristic consists in that an abutment (52) moves in an orbital path (a true circle in the illustration) and stop means (48, 49 etc.) has a part (48) which is transferred from one side to the other of the abutment in response to a single impulse of current at the end of each cycle (once per hour in the illustration) whereby the stop is automatically repositioned for engagement with the abutment at the end of the next succeeding cycle.

I claim:

1. A secondary clock of the impulse type comprising a clock train, impulse means, and

corrective means having a stop normally preventing the advance of said clock train beyond a predetermined point, said corrective means being operable to simultaneously remove the stop and advance the clock train. 70

2. In a secondary clock of the impulse type having a clock train, corrective means comprising a cam and a pin carried by the clock train, and a stop lever having a stop lying normally in the path of said pin, a second stop slightly advanced beyond the first stop and normally lying outside the path of said pin, and an arm on said lever cooperating with said cam to advance the clock train when the lever is operated, said operation simultaneously withdrawing the first stop from and introducing the second stop into the path of the pin. 80

3. In a secondary clock of the impulse type having a clock train including a shaft, a ratchet wheel fixed thereto and an impulse magnet for advancing the ratchet wheel and shaft, the combination of a cam and pin carried by said shaft, a stop lever, a magnet for moving said stop lever, said stop lever being in operative position prior to a predetermined time whereby said pin and shaft are not allowed to advance beyond a predetermined position and said stop lever being moved at said predetermined time to advance said cam and shaft. 90

4. A secondary clock normally operable by recurrent impulses from a master clock comprising a stop for blocking the advance of the clock train immediately preceding predetermined time intervals if the clock be fast, and non-polarized electromagnetic means for concomitantly rendering said stop inoperative and advancing the clock beyond the stopped position at said intervals. 100

5. A secondary clock normally operable by recurrent impulses from a master clock comprising a stop for blocking the advance of the clock train immediately preceding predetermined time intervals if the clock be fast, and non-polarized electromagnetic means for concomitantly releasing the clock train and repositioning the stop to block the train at the end of the next interval. 110

6. A secondary clock normally operable by recurrent impulses from a master clock, an abutment moving in an orbital path with the clock train, a stop for blocking the train when the abutment reaches a predetermined point in said path, said stop including a part disposed in front of said abutment when the latter reaches said point, and means operative in response to a single impulse of current to transfer said part from the front to the rear of said abutment, thereby permitting continued advance of the clock train. 120

7. A secondary clock normally operable by recurrent impulses from a master clock, an 130

- abutment moving in an orbital path with the clock train, a stop for blocking the train when the abutment reaches a predetermined point in said path, said stop including a part 5 disposed in the path of said abutment when the latter reaches said point, and means operative in response to a single impulse of current to transfer said part from one side to the other of said abutment, thereby permitting continued advance of the clock train.
8. A secondary clock normally operable by periodic impulses from a master clock, an abutment moving in an orbital path through recurrent cycles, a stop arranged to block the 15 clock train by engagement with said abutment when the abutment reaches a predetermined point in said path, and means operative in response to a single impulse to release the clock train and reposition the parts again to block the train after the abutment has completed another cycle around said orbital path.
9. A secondary clock system of the impulse type comprising a clock train, means including an electromagnetic winding for moving the clock train in recurrent cycles, means for terminating further advance of the clock train at a predetermined point in each cycle if the clock is fast, means including a second 25 electromagnetic winding in the secondary clock controlling further advance of the clock train, and circuits for said windings respectively whereby one may be rendered operative independently of the other.
- 30 10. A secondary clock system of the impulse type comprising a master clock for transmitting to the secondary clock regular driving impulses and periodic starting impulses, a plurality of conductors for separately transmitting said impulses to the secondary clock, clock-advancing means in each secondary clock normally responsive to said driving impulses, said means including an electromagnetic winding connected to one of said conductors, means in each secondary clock for limiting the advance of the clock train beyond a predetermined point in each predetermined cycle of time if the clock is fast, and means 35 in each secondary clock controlling further advance of the clock after it has been corrected, said last means including an electromagnetic winding in the other of said conductors.
- 40 11. A secondary clock of the impulse type in which the clock train is advanced intermittently by equal steps, means in the clock for limiting the advance of its clock train beyond a predetermined point in each predetermined cycle of time if the clock is fast, said means including an obstruction for physically blocking further advance, said obstruction having a back-and-forth movement to and from blocking position and permitting 45 further advance of the clock train when 50 momentarily moved out of said position, and means for periodically causing said obstruction to move out of said position and immediately back to said position.
12. A secondary clock of the impulse type 55 in which the clock train is advanced intermittently by equal steps, means in the clock for limiting the advance of its clock train beyond a predetermined point in each predetermined cycle of time if the clock is fast, said means including an obstruction for physically blocking further advance, said obstruction moving out of blocking position and back again in response to a single impulse thereby permitting further advance 60 of the clock train, and means for applying a momentary impulse to said obstruction at regular predetermined intervals.
- Signed by me at Springfield, Massachusetts, this 24th day of July, 1928. 65
